UNITED STATES PATENT OFFICE.

JOHN ROGERS, OF CLEVELAND, OHIO, ASSIGNOR OF ONE-HALF TO GUSTAV E. KÄPPLER AND GEORGE D. ADAMS, BOTH OF CLEVELAND, OHIO.

BAG-TIER SHEARS.

No. 899,765.

Specification of Letters Patent.

Patented Sept. 29, 1908.

Application filed November 2, 1907. Serial No. 400,337.

To all whom it may concern:

Be it known that I, JOHN ROGERS, a citizen of the United States, residing at Cleveland, in the county of Cuyahoga and State of Ohio, have invented certain new and useful Improvements in Bag-Tier Shears, of which the following is a specification.

This invention relates to mechanism for tying a bag, and particularly to means for severing a cord, after a portion of said cord has been wrapped and tied upon the gathered neck of a bag. Its object is to provide a durable and effective mechanism, operative in conjunction with a bag tying machine, for positively cutting off the cord which said machine wraps and ties upon the gathered neck of a bag.

A further object is to adapt cord-shearing mechanism to the type of bag tier shown and described in my application for patent filed June 20, 1907, and serially numbered 379,868.

To these ends my invention consists in the features and combinations hereinafter described and claimed, a structural arrangement thereof being illustrated in the accompanying drawings in which

Figure I is a plan view, and Fig. II is a front elevation of the essential parts of a bag tying mechanism, showing my improved cord-shearing arrangement. Fig. III is a rear elevation of the shearing mechanism, certain parts being in section on line III—III of Fig. I. Fig. IV is a detailed plan view with the longer shear blade in section on line IV—IV of Fig. III.

The construction and operation of the tier, by which a knot such as shown in Fig. III is formed, is fully described in my above mentioned application serially numbered 379,868, but in order that my present improvements may be comprehended, I will first proceed with a brief description of the tier, employing the same reference characters as are used in the aforesaid application.

The superimposed plate 77 upon the plate 76 forms a slidable box-frame *w* for the tier mechanism, which has a recess 78 in which a rotary shuttle *x* is mounted, the latter having gear teeth about its periphery whereby it is driven as required in the direction of the arrow in Fig. I by the driving shaft 84 through the large gear wheel 85, and the intermediate pinions 92 and 93. A gap 79 in said shuttle

is arranged to register with the recess 78, to receive the gathered neck *b* of a bag.

A cord 130 is first threaded through a tension device 129 secured to the tier frame, and then through an eye in the forward end of an eye-bar *z*, the latter being universally pivoted to the frame at 103, and its rearward end guided in an elliptical guide 105. A cam wheel *y* has spur gear teeth and is driven by a pinion 86 on the shaft 84. A lever 109 rotatably mounted on the shaft 84 engages in the 65 groove 107 in the wheel *y* at one end, and operates the eye-bar *z* through a link 111 hinged between its other end and an arm 112 operatively connected to the eye-bar.

A cord clamping dog 81 is pivoted upon 70 the shuttle *x*, and adapted to spring against a lug 80 upon said shuttle, so as to catch and hold the end of the cord 130. Said cord clamp is opened at proper times by the cam levers 97 and 101, both of which levers are operated by certain projections on the wheel *y* engaging the releasing lever 94 against a spring, not shown, and thereby reciprocating the connecting bar 99, one end of the latter being hinged to the lever 97, and a pin thereon engaging the tail of the lever 101, as shown in Fig. I. Thus, the shuttle *x* starts from the position shown in the figures, the clamp 81 is opened to receive the free end of the cord and then closed thereon, whereby 85 the cord is wrapped twice or thrice about the bag-neck, and is released from said clamp by the lever 97, the latter being swung inward after the last wrap is made. Meanwhile a lateral loop 118, on the end of a rotatable 90 shaft 115, and terminating in a hook, is in position to receive the wraps of the cord as the shuttle carries the latter around the bag-neck. When the last wrap has been drawn into said loop 118, the end of the eye-bar *z* is 95 forced by the cam 108 to describe an elliptical movement about the hooked end of the loop 118, which throws a bight of the cord 130 into said hook. The rack cam 125 on the wheel *y* then engages the pin 126 on the 100 slidable rack 121, which forces the latter backward, thereby rotating the shaft 115 through its pinion 120 in mesh with said rack. This latter movement serves to rotate the loop 118, and its hooked end carries the aforesaid bight of cord upward between the wraps and the bag-neck, and then rearward therefrom, so that a knot is formed as shown in

Fig. III. In this position it is necessary to release the end of the cord from the clamp 81, and at the same time sever it at a point between the eye-bar *z* and the hooked end of 5 118, after which the hook shaft 115 is returned to its normal position by the spring 124, and the shuttle *x* continues its rotation to the position shown. With this explanation of the original machine, the following 10 110 description of my improved cord severing mechanism should be readily comprehended.

An approximately horizontal bar *a* of rectangular section is supported above the inner side of the central aperture of the shuttle *x* 15 upon the standards *c* and *d* secured to the tier frame *w*. The bar *a* and standard *c* may be integral, or both standards may be integral with the bar if desired, but herein they are shown bolted together. A long shear 20 blade *f* is vertically disposed above the loop 118, and adapted to reciprocate in suitable guides upon the bar *a*. As shown in Figs. III and IV, a recess is made in the bar *a* to guide said shear blade, but it is obvious that 25 other well known means may be provided for this purpose. A short shear blade *g* is fulcrumed upon the blade *f* by the pin *e* secured to the latter blade near its lower end, so that the cutting edges of said blades are opposed 30 to each other. The shear blades are kept in place by a plate *h* secured to the bar *a*, as shown. Another plate *k* is secured to and depends from the bar *a*, and has a recess *i* in its inner side adapted to receive a laterally 35 projecting lug *j* of the shorter blade *g*. A light spring *l* is attached at one end to the blade *f*, being bent upon itself so that its other end rests upon the bar *a*, as shown.

A bell-crank lever *m* has its vertical arm 40 fulcrumed to the bar *a* by a pin *n*, and the swinging end of its horizontal arm is slotted to receive a pin *o* projecting from the blade *f*. A horizontal angle lever *p* is fulcrumed at *q* to the frame structure of the tier *w*, and its 45 rearward end is provided with a pin *r* projecting downward into the groove 107 of the wheel *y*. A plain link *s* connects the forward end of the lever *p* to the horizontal wing of an angle link *t*, the vertical wing of the latter being operatively connected by the bolt *u* to the 50 depending end of the lever *m*.

The shearing mechanism is held out of operation while the pin *r* is engaging in the circular portion of the groove 107; and during 55 this interval the shear blades are held up above the cord, and are also opened because the lug *j* is in contact with the upper end of the recess *i*. The cord 130, which is led over the bar *a*, is free during this interval 60 from pressure by the spring *l*. But, the knot having been formed by the bight of cord *v*, Fig. III, being pulled up under the wraps and away from the bag neck *b* by the hooked loop 118, as hereinbefore described, 65 the shearing device operates quickly to sever

the cord at *v*. The cam 108 on the wheel *y* strikes the pin *r*, thereby swinging the lever *p*, which through its connections *s* and *t* swings the lever *m* to force down the shear blades. When the cutting edges of the shear 70 blades have straddled the cord, the lug *j* engages the lower end of the recess *i*, and as the blades are further depressed they are thereby forced to close and cut off the cord at the bight *v*. At the same time, the spring *l* 75 clamps the cord upon the bar *a*, so that said cord, which is under tension, cannot spring back through the eye in the bar *a* when it is severed. The various parts are returned to their first position of rest immediately after 80 the severing of the cord, and the tier *w* is carried backward away from the bag. Thus it is evident that the cord severing portion of the bag tying mechanism, as described herein, has been made positive and effective in 85 its operation, and as durable as shear blades are known to be.

I further point out and distinctly claim as my invention—

1. The combination with mechanism for 90 wrapping and tying a cord into a knot upon a bag-neck, of shear blades operative in conjunction with said mechanism and arranged to sever said cord after the latter has been tied and drawn into a knot, substantially as 95 set forth.

2. The combination with mechanism for 100 wrapping and tying a knot in a continuous cord upon a bag-neck, of a shearing device operative by said mechanism for severing said cord from the bag tie after the latter has been drawn into a knot, and clamping means adapted to hold said cord while it is being severed from the bag tie, substantially as set forth.

3. The combination with mechanism for 105 tying a bag, of a slidably mounted shear blade, means operative by said mechanism for reciprocating said blade, a corresponding shear blade fulcrumed to said slidable blade, 110 and means for swinging said fulcrumed blade, substantially as set forth.

4. The combination with mechanism for 115 tying a bag, of a shear blade slidably mounted thereon, means operative by said mechanism for reciprocating said blade, a shear blade fulcrumed to said slidable blade having a lateral projection, and means adapted to engage said lateral projection to swing said fulcrumed blade, substantially as set forth.

5. The combination of a rotary shuttle 120 having a recess adapted to receive the neck of a bag and means for wrapping a cord thereabout, means operative in connection with said shuttle for tying said cord, and a pair of shears operative in conjunction with said shuttle for severing said cord, substantially as set forth.

6. In a bag tying machine, the combination with mechanism for wrapping and tying 125

a cord comprising a rotary shuttle, a rotatable hook and a vibratile eye-bar, of a cam wheel operative in conjunction with said mechanism, a pivoted lever engaging said cam wheel, a pair of shears adapted to sever said cord, and operative connections between said lever and said shears, substantially as set forth.

7. In a bag tying machine, the combination with mechanism for wrapping and tying a cord comprising a rotary shuttle, a rotatable hook and a vibratile eye-bar, of a cam wheel operative in conjunction with said

mechanism, a pivoted lever engaging said cam wheel, a pair of shears adapted to sever 15 said cord, a lever connected to said shears, and operative connections between the said levers, substantially as set forth.

In testimony whereof I affix my signature in the presence of two subscribing witnesses 20 at Cleveland, Ohio, this 29th day of October, 1907.

JOHN ROGERS.
